UNITED STATES PATENT OFFICE.

JACOB HOFFMAN SPIGENER, OF TALLADEGA, ALABAMA.

PEN-HOLDER.

SPECIFICATION forming part of Letters Patent No. 419,083, dated January 7, 1890.

Application filed June 29, 1889. Serial No. 315,994. (No model.)

To all whom it may concern:

Be it known that I, JACOB HOFFMAN SPIGENER, a citizen of the United States, residing at Talladega, in the county of Talladega and 5 State of Alabama, have invented a new and useful Pen-Holder, of which the following is a specification.

My invention relates to improvements in pen-holders; and it consists in certain novel 10 features hereinafter described and claimed.

In the accompanying drawings, Figure 1 is a perspective view of a pen-holder constructed in accordance with my invention. Fig. 2 is a longitudinal section of the same. Fig. 3 is 15 a cross-section on an enlarged scale.

The handle A is of the usual form, and may be of any desired size. To the end of the handle I secure the divided sleeve B, which is constructed of any suitable light metal 20 having a slight spring action, so that its free end may be compressed when so desired. To the inner side of this sleeve, near the free end of the same, I secure a series of U-shaped plates C, which are connected together and 25 to the said sleeve by a single rivet D, passing through the said sleeves and the ends of the plates. The diameters of these U-shaped plates C increase from the inner or bottom plate to the outer or top plate, so as to adapt 30 the pen-holder to pens of different sizes, and the said plates increase in length from the top or outer plate to the bottom or inner plate, so that the pen may be readily engaged over the proper plate. A ring or collar E is mounted on the sleeve B and adapted 35 to slide thereon, and is provided with an internal pin F, which passes through a longitudinal opening in the sleeve, and thereby guides the said ring or collar in its move- 40 ments.

In practice the pen is fitted over the proper plate C and the collar or ring is then moved toward the free end of the divided sleeve,

consequently compressing the said end of the sleeve, so as to clamp the pen in position. 45 When it is desired to release the pen, the collar is moved away from the end of the sleeve, when the pen can be readily removed.

It will be observed that my improved pen-holder is very simple in its construction, and 50 can be manufactured at a slight cost. Any size pen may be used with the pen-holder, and the pen can be quickly secured therein, so that it will be held firmly and not be liable to drop out.

Having thus described my invention, what I claim, and desire to secure by Letters Patent, is—

1. A pen-holder consisting of a handle, a series of concentric U-shaped pen-holding 6c plates secured to and projecting beyond the end of the handle, the said plates decreasing in length from the inner to the outer plate of the series, whereby the ends of all the plates are exposed, a sleeve secured to the handle 65 and extending over the inner ends of the plates, and a collar mounted on the sleeve and adapted to compress the same around the plates, as set forth.

2. The improved pen-holder consisting of a 70 handle, a divided sleeve secured thereto, a series of U-shaped plates, of various diameters and of varying lengths, secured within the said sleeve, and a collar sliding on the sleeve and adapted to compress the end of 75 the same and provided with an internal pin engaging the longitudinal opening in the sleeve, as set forth.

In testimony that I claim the foregoing as my own I have hereto affixed my signature in 80 presence of two witnesses.

JACOB HOFFMAN SPIGENER.
